UNITED STATES PATENT OFFICE.

CHARLES E. SCRIBNER, OF CHICAGO, ILLINOIS, ASSIGNOR, BY MESNE ASSIGNMENTS, TO THE WESTERN ELECTRIC COMPANY, OF SAME PLACE.

NIGHT-SIGNAL CIRCUIT FOR TELEPHONE-EXCHANGES.

SPECIFICATION forming part of Letters Patent No. 293,196, dated February 5, 1884.

Application filed June 20, 1881. (No model.)

To all whom it may concern:

Be it known that I, CHARLES E. SCRIBNER, of Chicago, Illinois, have invented a certain new and useful Improvement in Night-Signal Circuits for Telephone-Exchanges, of which the following is a full, clear, concise, and exact description.

My invention consists in continuing the individual line or wire of any subscriber to the offices of many subscribers, and thereby providing for many subscribers a means of signaling the central station.

Figure 1 shows three subscribers' stations, 1 2 3, connected with switches *a b c* at the central office in the usual manner. The night-call apparatus consists of annunciator *d* and bell *e*, placed in the circuit of battery *f*.

Fig. 2 shows another well-known way of connecting stations 1', 2', and 3' with connecting plates or bolts *a' b' c'* at the central office. The night-call is the same as shown in Fig. 1, and consists of annunciator *d'* and bell *e'* in circuit of battery *f'*. The night-call apparatus is the same, whatever the system of connecting the subscriber with the central office, and is connected with any one of the switches or bolts of the subscribers, as shown at *a* and *a'*.

In Fig. 1 the telephone-line *g* of station 1 is connected with many other stations, 2 3, &c., by the line *h*, and at the central office, by means of the plug and cord and line *i*, with the armature and shutter of annunciator *d*, through said annunciator and battery *f* to ground, as shown.

Any subscriber, by moving his switch so as to connect line *h* to ground, completes the circuit of battery *f*. As shown at station 3, Fig. 1, simply removing the telephone from the switch thus completes the circuit of the battery from line *h* through connected lines of stations 2 and 3. When the lines are open at the central office, as shown in Fig. 2, I provide keys *k*, one at each station, which, when depressed, connect the line *h* directly to ground. When the circuit is completed, the shutter of the annunciator is at once thrown down and the battery-circuit broken from the line *i* and directed through the bell *e*. The bell continues to ring when its circuit is thus closed to

battery until the attendant is aroused. If the battery were not instantaneously disconnected from line *i* when line *h* is connected to ground, the bell at station 1 in the circuit of line *g* would ring.

The listening-operator's outfit is not shown in the drawings. It may be constructed, connected, and operated in the usual manner.

When the telephone of any given station is hung on the switch-lever, the telephone-line 6c. of the station is disconnected from ground and connected with the outer common line. Thus at station 1, Fig. 1, telephone-line *g* is shown cut off from the telephone and ground and connected with the outer line, *h*. At station 65 3, Fig. 1, the telephone is shown removed from the switch-lever. The telephone-line of station 3 is thus cut off from line *h* and connected through the telephone to ground, as shown.

The switches or spring-jacks *a b c*, Fig. 1, are of the form well known as the "jack-knife." They are so constructed that when a plug is inserted the blade or circuit-changing piece is wedged away from the insulated contact-point of the switch. The telephone-line is thus cut off when a plug is inserted, as shown at switch *a*, Fig. 1. In Fig. 2 the telephone-lines terminate at the central office in connecting plates or bolts *a', b', and c'*, and are not connected together or to ground at the central office. It is therefore unnecessary to provide jackknife-switches. Jackknife-switches might, however, be used. The telephone-lines, as shown in Fig. 2, being normally open at the central office, it is unnecessary to provide jackknife-switches upon the switch-board, for they cannot be disconnected or cut off unless they have been previously connected.

As before stated, the telephone-lines, as shown in Fig. 2, are normally open at the central office, and are not connected at the central office with a common line, with one another, or with anything else except the terminal plates 95 or bolts *a', b', and c'*.

I claim--

The combination, in a telephone-exchange, with several individual telephone-lines connected together by a common outer line, of a 100

branch circuit to ground at the central office containing a battery and annunciator, said branch being adapted to be connected at the central office to any one of the telephone-lines, 5 and switching apparatus at each subscriber's station, whereby the branch containing the battery and annunciator may be closed to ground

at any subscriber's station through one or more of the individual lines and the common outer line.

CHARLES E. SCRIBNER.
